NONREFILLABLE BARREL

Howard L. Newton and Herman Merker, Milwaukee, Wis., assignors to Pressed Steel Tank Company, Milwaukee, Wis., a corporation of Wisconsin

Application July 11, 1936, Serial No. 90,109

12 Claims. (Cl. 220—86)

This invention relates to a non-refillable barrel of the type designed for use in transporting and storing liquids which are to be dispensed therefrom.

5 5 The non-refillable barrel embodying the several structures contemplated by the present invention is of the same general type as that forming the subject matter of the application of R. C. Brushe, filed August 19, 1935, Serial No. 10 10,36775, granted April 13, 1937, Patent No. 2,077,210 and assigned to the same assignee as this application.

Non-refillable barrels of the character disclosed in the Brushe application comprise generally a 15 closed container having a dispensing opening, a pipe leading from the opening to a point adjacent the bottom of the container, a check valve associated with the inner portion of the pipe to preclude flow through the pipe into the interior 20 of the barrel while providing for flow from the interior of the barrel out through the pipe, means connecting the pipe with the margin of the dispensing opening, and a locking device for securing the pipe against removal, the locking device 25 being of such character that it is releasable only in a predetermined manner and with the aid of special releasing tools or devices.

One of the principal objects of the present invention is to provide a highly effective type of locking device which is so compactly and closely organized as to occupy a minimum space and as to be susceptible of economical production from materials and by means of facilities ordinarily available. The locking device in all of its several 30 35 embodiments positively secures the pipe or conduit against removal by unauthorized persons and yet may be readily manipulated to release the pipe by those acquainted with the manner in which it is operated and equipped with the special tools provided for its manipulation.

In several embodiments of the invention the parts are so organized that when the pipe is removed the locking device is withdrawn with it. 40 45 Only a simple type of check valve, one not likely to get out of order, remains in the barrel.

Other objects and advantages reside in certain novel features of the construction, arrangement and combination of parts which will be herein-after more fully described and particularly pointed out in the appended claims, reference being had to the accompanying drawings, forming a part of this specification, and in which:

Figure 1 is a fragmentary view partly in trans- 50 55 verse vertical section and partly in elevation

showing a non-refillable barrel embodying the present invention;

Figure 2 is a fragmentary view in vertical section taken on line 2—2 of Figure 1;

Figure 3 is a fragmentary view in elevation showing one type of tool which may be employed for releasing the locking devices incorporated in the embodiment shown in Figures 1 and 2 and also in the embodiment shown in Figures 5 to 8, inclusive;

Figure 4 is a view in transverse cross section 10 taken on line 4—4 of Figure 3;

Figure 5 is a fragmentary sectional view, parts being shown in elevation for the sake of simplicity in illustration showing another type of locking 15 device;

Figures 6 and 7 are views in horizontal cross section taken on lines 6—6 and 7—7, respectively, of Figure 5;

Figure 8 is a fragmentary view partly in side 20 elevation and partly in vertical cross section, the plane of the section being designated by line 8—8 in Figure 6; and

Figure 9 is a view similar to Figure 5 showing 25 still another type of locking device.

Referring to the drawings, and more particularly to Figure 1, the numeral 1 designates the body of a barrel or similar container which is entirely closed except for the provision of a single opening 2. Of course, a suitable vent may be provided, one such being designated by dotted lines at V in Figure 1.

A bushing 3 has a reduced inner end 4 inserted in the opening 2. The bushing is flanged as at 5 and the periphery of this flange is welded as at 6 to the top of the container so as to permanently 30 35 secure the bushing 3 in place.

A vertical pipe or conduit 7 is provided and has its upper end threaded into a connecting ring 8. A weld 9 may also be provided between the upper end portion of the pipe 7 and the ring 8 to rigidly secure these parts together. The periphery of the ring 8 is externally threaded so that it may be threaded into the bushing 3. The upper surface of the ring 8 is provided with a suitable number of openings 10 to adapt the ring 40 45 and its pipe 7 to be applied and removed, under certain conditions, with the aid of a spanner wrench or other similar tool. The ring 8 and upper end of the conduit may be protected by means of a cap 11 threadedly interconnected with the bushing 3. A gasket 12 is usually provided between the flange of the cap 11 and the upper end of the bushing so that when the cap 50 55 is tightened up it will provide a sealed closure.

The lower end of the pipe 7 is interfitted with a connecting sleeve 15 and is welded thereto as indicated at 16. The lower end of this sleeve 15 is reduced as indicated at 17 and extends down 5 into the upper end of a valve casing designated generally at 18.

The valve casing 18 is, as shown, vertically positioned in the lower part of the barrel and has its lower end permanently and rigidly secured to but 10 slightly spaced from the bottom of the barrel. For this purpose foot pieces 19 may be integrally formed with or suitably secured to the lower end of the valve casing and welded as at 20 to the barrel bottom. The lower end of the valve casing 15 is provided with an opening 21 and around the inner margin of the opening with a downwardly flaring valve seat 22. A valve 23 coats with the valve seat 22 and when engaged with the seat as shown in Figure 1 closes the opening 21. Stop pins 24 limit the movement of the valve 23 away 20 from its seat.

Means is provided for locking the connecting sleeve 15 to the valve casing and in this form of the invention comprises locking balls 25 similar 25 to ball bearings and accommodated in transverse openings 26 provided in the reduced lower end 17 of the connecting sleeve. The openings 26 are so shaped and dimensioned as to limit the distance at which the balls may be projected outwardly 30 therethrough but they do allow sufficient projection of the balls to enable them to have locking engagement with the tapered inner surface 27 of the upper end of the valve casing.

For forcing the balls 25 into locking engagement 35 with the tapered surface 27 of the valve casing an expanding bushing 28 is provided. The upper portion of the outer periphery of this bushing 28 is threadedly interconnected with the sleeve 15 as indicated at 29. Below this threaded portion 40 29 the exterior or outer periphery of the bushing 28 is smoothed but is provided with an inclined surface 30 which, as the bushing is threaded down into the sleeve, acts on the balls 25 to force them out to the position shown in 45 Figure 1. In this position axial movement of the pipe 7 and its connecting sleeve 15 relative to the valve casing 18 is positively limited. Hence, the ring 8 may not be unthreaded from the bushing 4 and the pipe 7 may not be removed. The upper 50 end of the bushing 28 is provided with slots 31 designed to coat with a special tool in order to provide for the manipulation or turning of the bushing in either direction by authorized persons.

Such a tool is shown in Figures 3 and 4 and 55 consists of an elongated shank 35 provided with a cross handle 36 at its upper end and with laterally extending keys 37 adjacent its lower end designed to interfit with the slots 31. Of course, it is to be understood that these keys 37 and the 60 slots 31 may be of any special shape or configuration.

In this embodiment of the invention when the barrel is full of oil the cap 11 may be removed and any appropriate type of pump may be connected up with the bushing 3 and conduit 7 to dispense the oil from the barrel. However, any down-flow of oil through the pipe 7 back into the barrel is prevented by the check valve 23. Access to this check valve or removal of the pipe 7 is effectively precluded except by persons having 70 knowledge of the special way in which the device is constructed and equipped with the tool such as the tool shown in Figures 3 and 4. By inserting the tool down through the conduit 7 and 75 engaging its keys 37 with the slots 31, the ex-

5 panding bushing 28 may be backed up sufficiently to allow the balls 25 to move back against the reduced lower end 28' of the bushing. When the expanding bushing 28 is backed up so that the reduced portion 28' is in alignment with the balls then there is no resistance holding the balls in 10 position and backing out the connecting ring 8 permits the balls to move axially inwardly by reason of the increasing pressure exerted by the inclined surfaces 27 of valve body 13. With the 15 balls in their released position, that is, out of engagement with the inwardly sloping surface 27 of the valve casing, a wrench may be applied to the ring 8 to remove the ring together with the conduit 7, connecting sleeve 15 and the locking device. The barrel may then be conveniently 20 refilled.

The form of the invention shown in Figures 5 to 8, inclusive, is identical with that above described except that a differently constructed locking arrangement is provided. As in the other embodiment of the invention the conduit 7, which is connected at its upper end to the barrel as before is welded as at 16 to a connecting sleeve designated at 40. The connecting sleeve has a 25 reduced lower portion 41 fitted in the upper end of the valve casing 18. Transverse openings 26 are provided in this reduced portion of the connecting sleeve to accommodate locking balls 25 as before. However, these locking balls 25 instead of coating with an inwardly sloping or included surface on the valve casing are adapted to be seated in vertical grooves 42 provided on the inside of the valve casing, and when so seated prevent turning of the connecting sleeve 35 40 and consequently the conduit 7. Moreover, in this form of the invention a different type of structure is provided for moving the balls to locking position and providing for their return to released position.

A flanged and apertured supporting plate 43 is secured in the lower end of the connecting sleeve by means of set screws 44. An oscillating cam 45 is supported on this plate 43 and is confined to its oscillating movement by the plate and 45 by means of an internal shoulder 46 formed on the connecting sleeve. This cam is also apertured so that the liquid can freely flow through the cam and the mounting plate. The cam has curved or inclined surfaces 47 designed to wipe 50 against the balls 25 and force these balls outwardly until they ride on the high points 49 of the cam, in which position the balls will be projected into the grooves 42 and the parts locked 55 into position. Transverse slots 50 are provided in the upper surface of the cam so that a tool such as shown in Figure 3 may be employed to rotate the cam. In order to releasably secure the cam in position to maintain the balls projected 60 into locking position or in position where the balls are permitted to fall back to released position by gravity a ball projected detent 51 is provided in the mounting plate 43 and is engageable with recesses 52 and 53 provided on the undersurface of the cam 45. The extent to which the cam may be 65 oscillated in either direction is positively limited by means of a stop pin 54 fixed to the cam and projecting down into an arcuate groove 55 provided in the mounting plate.

In Figure 9 there is illustrated still another 70 type of locking device which may be employed for securing the connecting sleeve at the lower end of the pipe 7 and consequently also the pipe 7 against rotation. In Figure 9 the connecting sleeve is designated at 56 and is provided in its 75

reduced lower portion 57 with a plurality of circumferentially spaced bolt receiving openings 58. The valve casing 18 has an opening 59 at its upper portion to receive the inner end of a bolt housing 60. A weld 61 secures the bolt housing to the bolt casing. A bolt 62 is slidably mounted in the housing and is projected inwardly by means of a spring 63, the spring being interposed between the inturned annular flange 64 provided at the outer end of the bolt housing and a shoulder presented by the guide portion 65 of the bolt. The extent to which the bolt is projected inwardly by the spring is limited by the engagement of an integral head or collar 62 provided on the bolt with the inturned flange 64. The lower end of the connecting sleeve is beveled as at 67 so that when the sleeve is introduced into the valve casing this beveled end 67 will cooperate with the beveled edge 68 of the bolt to push the bolt back until one of the openings 58 comes into alignment therewith whereupon the spring 63 will thrust the inner end of the bolt into the aligned opening 58 and the device will be locked in place. The device may be released and the pipe 1 removed only by introducing a special tool down through the pipe 7 and operating it to thrust the bolt outwardly out of the opening 58 in which it is engaged, thereupon the pipe 7 may be removed as in the other embodiments of the invention. The special tool may be identical with that shown and described in the Brushe application above referred to and its parts are shown in dotted lines in Figure 9 and designated at 22^a, 23^a and 25^a.

While we have shown and described several constructions in which the invention may be advantageously embodied, it is to be understood that these constructions have been selected merely for the purpose of illustration or example, and that various changes in the size, shape and arrangement of the parts may be made without departing from the spirit of the invention or the scope of the subjoined claims.

The invention claimed is:

1. A non-refillable barrel comprising a container having an opening through which its contents may be dispensed, a conduit in said container, means for releasably connecting one end of the conduit to the margin of the opening, a valve casing within and secured to the container, a valve in said valve casing for preventing flow therethrough into the container while providing for flow of the contents of the container out through the valve casing, a connecting sleeve secured to the lower end of the conduit and interfitting with the valve casing, and a locking element for securing said connecting sleeve to said valve casing, means constraining the locking element to move transversely with respect to the locking sleeve from locked to released position and vice versa, in combination with a special tool insertible through the pipe for manipulating said transversely shifting locking element.

2. A non-refillable barrel comprising a container having an opening through which its contents may be dispensed, a conduit in said container, means for releasably connecting one end of the conduit to the margin of the opening, a valve casing within and secured to the container, a valve in said valve casing for preventing flow therethrough into the container while providing for flow of the contents of the container out through the valve casing, a connecting sleeve secured to the lower end of the conduit and interfitted with the valve casing, locking balls car-

ried by the portion of the sleeve interfitted with the valve casing, said valve casing being cooperable with the balls when they are projected outwardly from the sleeve, to secure the sleeve against removal from the valve casing, and means for projecting said balls outwardly into locking position.

3. A non-refillable barrel comprising a container having an opening through which its contents may be dispensed, a conduit in said container, means for releasably connecting one end of the conduit to the margin of the opening, a valve casing within and secured to the container, a valve in said valve casing for preventing flow therethrough into the container while providing for flow of the contents of the container out through the valve casing, a connecting sleeve secured to the lower end of the conduit and interfitting with the valve casing, locking balls carried by the portion of the sleeve interfitted with the valve casing, said valve casing having an inwardly sloping surface with which said balls are adapted to have interlocking engagement when projected, and means for projecting the balls.

4. A non-refillable barrel comprising a container having an opening through which its contents may be dispensed, a conduit in said container, means for releasably connecting one end of the conduit to the margin of the opening, a valve casing within and secured to the container, a valve in said valve casing for preventing flow therethrough into the container while providing for flow of the contents of the container out through the valve casing, a connecting sleeve secured to the lower end of the conduit and interfitting with the valve casing, locking balls carried by the portion of the sleeve interfitted with the valve casing, said valve casing having an inwardly sloping surface with which said balls are adapted to have interlocking engagement when projected, means for projecting the balls, and comprising an expanding bushing threadedly interconnected with the sleeve and having an inclined surface cooperable with the balls.

5. A non-refillable barrel comprising a container having an opening through which its contents may be dispensed, a conduit in said container, means for releasably connecting one end of the conduit to the margin of the opening, a valve casing within and secured to the container, a valve in said valve casing for preventing flow therethrough into the container while providing for flow of the contents of the container out through the valve casing, a connecting sleeve secured to the lower end of the conduit and interfitting with the valve casing, locking balls carried by the portion of the sleeve interfitted with the valve casing, said valve casing having grooves into which said balls may be projected to lock the sleeve to the valve casing, and means for projecting said balls into locking engagement with said grooves.

6. A non-refillable barrel comprising a container having an opening through which its contents may be dispensed, a conduit in said container, means for releasably connecting one end of the conduit to the margin of the opening, a valve casing within and secured to the container, a valve in said valve casing for preventing flow therethrough into the container while providing for flow of the contents out through the valve casing, a connecting sleeve secured to the lower end of the conduit and interfitting with the valve casing, locking balls carried by the portion of the sleeve interfitted with the valve casing, said

- valve casing having means thereon with which said balls are engageable when projected to lock the sleeve and valve casing against disassembly, and cam means for projecting said balls.
5. 7. A non-refillable barrel comprising a container having an opening through which its contents may be dispensed, a conduit in said container, means for releasably connecting one end of the conduit to the margin of the opening, a valve 10 casing within and secured to the container, a valve in said valve casing for preventing flow therethrough into the container while providing for flow of the contents of the container out through the valve casing, a connecting sleeve 15 secured to the lower end of the conduit and interfitted with the valve casing, locking balls carried by the portion of the sleeve interfitted with the valve casing, said valve casing having means thereon with which said balls are engageable 20 when projected to lock the sleeve and valve casing against disassembly, cam means for projecting said balls and including an apertured mounting plate secured to the sleeve, an apertured cam supported for oscillation on the mounting plate 25 and having camming surfaces engageable with the balls.
8. A non-refillable barrel comprising a container having an opening through which its contents may be dispensed, a conduit in said container, means for releasably connecting one end 30 of the conduit to the margin of the opening, a valve casing within and secured to the container, a valve in said valve casing for preventing flow therethrough into the container while providing for flow of the contents of the container out 35 through the valve casing, a connecting sleeve secured to the lower end of the conduit and interfitted with the valve casing, locking balls carried by the portion of the sleeve interfitted with the valve casing, said valve casing having means 40 thereon with which said balls are engageable when projected to lock the sleeve and valve casing against disassembly, cam means for projecting said balls and including an apertured mounting 45 plate secured to the sleeve, an apertured cam supported for oscillation on the mounting plate and having camming surfaces engageable with the balls, and cooperating means between the mounting plate and cam plate for releasably securing the cam plate in either locking or released 50 position.
9. A non-refillable barrel comprising a container having an opening through which its contents may be dispensed, a conduit releasably interconnected with the margin of the opening and 55 extending into the barrel, a check valve for preventing flow of liquid through the conduit into the barrel but allowing flow of liquid from the barrel through the conduit to the exterior, and a locking device within the barrel for preventing 60 removal of the conduit and comprising a member
- fixed in position within the barrel and a locking element cooperable with said member and with the conduit, said member and said conduit having means supporting said locking element for transverse shifting movement with respect thereto from locking to release position and vice versa in combination with a special tool adapted to be applied to said locking element to shift the same to released position.
10. A non-refillable barrel comprising a container having an opening through which its contents may be dispensed, a conduit in said container, means for releasably connecting one end 10 of the conduit to the margin of the opening, a valve casing within and secured to the container, 15 a valve in said valve casing for preventing flow therethrough into the container while providing for flow of the contents of the container out through the valve casing, a connecting sleeve secured to the lower end of the conduit and interfitted with the valve casing, said sleeve having a bolt hole, and a transversely shiftable bolt mounted on the valve casing and engageable with the bolt hole to secure the pipe against removal.
11. A non-refillable barrel comprising a container having an opening through which its contents may be dispensed, a conduit in said container, 20 means for releasably connecting one end of the conduit to the margin of the opening, a valve casing within and secured to the container, 25 a valve in said valve casing for preventing flow therethrough into the container while providing for flow of the contents of the container out through the valve casing, a connecting sleeve secured to the lower end of the conduit and interfitted with the valve casing, said sleeve having a bolt hole, a bolt mounted on the valve casing and engageable with the bolt hole, and a spring for urging the bolt into engagement with the bolt hole, in combination with a special tool insertable 30 through the conduit for releasing the bolt.
12. A non-refillable barrel comprising a container having an opening through which its contents may be dispensed, a conduit in said container, means for releasably connecting one end 35 of the conduit to the margin of the opening, a valve casing within and secured to the container, a valve in said casing for preventing flow therethrough into the container while providing for flow of the contents of the container out 40 through the valve casing, a locking device between the inner end of the conduit and the valve casing releasable in a predetermined manner and by means of special tools introduced through the conduit, means supporting said locking device or 45 said conduit in its released position, said locking device when released being removable with the conduit and its connecting means leaving only the valve casing and its valve in the container.

HOWARD L. NEWTON. 60
